UNITED STATES PATENT OFFICE.

CHARLES L. SPENCE, OF STURGIS, MICHIGAN.

MANIFOLDING OR DUPLICATING PAPER.

1,306,785.

Specification of Letters Patent. Patented June 17, 1919.

Application filed July 3, 1915. Serial No. 37,819.

To all whom it may concern:

Be it known that I, CHARLES L. SPENCE, a citizen of the United States, residing at Sturgis, in the county of St. Joseph and

5 State of Michigan, have invented a certain new and useful Improvement in Manifolding or Duplicating Paper, of which the following is a full, clear, and exact description, reference being had to the accompanying drawings.

This invention relates to paper, such as is particularly adapted for use in the making of duplicate records through the use of transfer material whereby the writing on an 15 original sheet will be reproduced upon a second sheet. A large field for the use of such paper is the production of triplicate sales books wherein an original and two copies of an entry may be made by one and 20 the same writing operation. The particular paper to which this invention relates is a double sheet, one section whereof is ordinary paper which is adapted to be printed upon and to be written upon directly by pencil or 25 typewriter, the other section being permeable whereby the transfer material taken upon the back or under side thereof from a sheet of such material when the original sheet is written upon by a pen, pencil, or typewriter, 30 will strike through such second section to the front face thereof, whereby it will be clearly legible on the front of this second or duplicate section. For the purpose of making a third copy of the writing, an additional 35 sheet of paper may be placed beneath the duplicate sheet, with a leaf of "full" carbon or transfer paper interposed between the second section and the third sheet, whereby the pressure created in writing upon the first 40 section will cause a transfer from the full carbon sheet to be made upon the back of the second section and upon the front or upper surface of the third sheet or section. Books or pads prepared with a carbon sheet 45 of the character referred to and with groups or series of the three sheets or sections suitably arranged constitute a triplicate sales book such as referred to hereinbefore—although it will be understood that paper produced in accordance with my invention is 50 not limited in its applicability to this particular use.

It is the general object of this invention to produce a permeable paper which will be 55 clean and remain clean in operation; which

will retain its permeable qualities permanently; which will be capable of and well adapted for receiving printing thereon; which will be firm and remain firm; and which will secure a permanent record of the 60 matter transferred thereto. Further and more limited objects will appear hereinafter.

In the drawings forming part hereof, Figure 1 shows a perspective view of a double sheet, one section whereof is of ordinary paper and the other section whereof is of permeable paper, the paper being rendered permeable in the manner hereinafter explained, the sections of the sheet being shown as detachably connected along a perforated line; 65 and Figs. 2, 3 and 4 show perspective views of a triplicate book made up from series of original, duplicate, and triplicate leaves and a full carbon sheet, the original and duplicate leaves being of the type shown in Fig. 1, 70 and these views showing successive steps in the manipulation of such books.

Describing by reference characters the various parts illustrated herein, 1 denotes the original and 2 the duplicate leaf, said leaves 80 being preferably divided by a perforated line 3 and the duplicate leaf being provided with a stub 4 to which it may be detachably connected through a perforated line 5. For convenience of manipulation, the original 85 leaf may be somewhat shorter than the duplicate leaf, whereby some clearance may be provided between the severing line 5 and the adjacent or upper end of the original. 7 indicates a triplicate sheet which may be 90 placed beneath the double sheet just described and which is secured at one end. The alternating stubs projecting from the duplicate and triplicate sheets may be conveniently stitched or stapled to a back 9, 95 this back being provided with an extension forming a cover 10, which may be a side-folding cover connected to an intermediate side portion 11 projecting from the back. Secured to the lower end of the back 9 is a 100 carbon or transfer sheet 12, which is coated on both sides with transfer material, as pencil carbon, and which is known to the trade as "full" carbon. It is evident that this transfer sheet 12 may be secured to the bottom of the pad in any other desired or convenient manner; also that it may, in certain cases, be secured to the side of the pad. For convenience of manipulation, either or both corners of the carbon sheet 12 may be 110

cut away, as indicated at 13, and each triplicate sheet may be provided with a notch 14 in the corresponding corner.

As previously stated, the duplicate leaf 5 or section 2 of the double sheet is permeable, whereby material transferred to the under or back surface thereof will strike through the leaf to the front or top surface thereof, whereby it will be clearly and easily legible. 10 I am aware of the fact that it has been proposed to make a duplicate leaf wherein one section is transparent in order that writing or transfer material which is applied to the back or under surface thereof may be legible 15 from the front or top surface. I am also aware of the fact that it has been proposed, in order to secure this result, to use tissue paper for the duplicate sheet. This paper, however, is obviously objectionable because 20 of its lack of body and because its use renders necessary the use of like material for the original or upper sheet or else necessitates fastening together two separate sheets of different kinds of paper. I am also aware 25 of the fact that it has been proposed to make a duplicate sheet of the same kind of paper as the original sheet and to render the duplicate sheet transparent or translucent by means of oil. Such paper, however, 30 is open to the serious objection that it is practically impossible to prevent the oil from soiling the adjacent sheets and the hands of the operator; also that the oil, being liquid at ordinary atmospheric temperatures, 35 will be gradually removed from the duplicate sheet, and especially where this sheet happens to come in contact with anything of an absorbent nature, so that the sheet loses its translucency or transparency. 40 A further objection to the use of such liquids as oils for the production of a transparent or translucent sheet is that it renders the paper practically useless for printing purposes; as for duplicating thereon the headings or other data which are applied to the 45 original sheet; also the saturation of the duplicate sheet with a liquid renders it soft and objectionably pliable.

In order to produce a paper which is free 50 from the objections noted, I coat and saturate the paper from which the duplicate sheets are to be made with a substance which is solid at normal atmospheric temperatures and which is capable of rendering the paper 55 permeable. As at present advised, I prefer to use stearic acid for this purpose, preliminarily heating the same to place it in a molten liquid condition and applying this liquid stearic acid to the paper. This may 60 be done by a machine such as is used for the purpose of waxing paper to render it waterproof, such machine being of the well-known type wherein the material to be applied to the paper (in this case, stearic acid) is contained within a steam-heated 65

trough, there being a roller revolving in this trough. The paper is led over this roller, which revolves in the trough, dipping into the molten stearic acid therein, and thus supplies the liquid coating material to the 70 paper; the surplus material is removed by means of a scraper conveniently placed and contacting with the coated side of the paper, and the coating is set or hardened by drawing the paper over chilled rolls. The molten 75 stearic acid, contacting with the paper, quickly strikes through the same, and the operation of treating the paper may be conducted with the same facility and speed as the operation of coating paper with wax or 80 paraffin. The paper thus prepared possesses all of the advantages hereinbefore noted, and these advantages make it particularly useful for the production of triplicate sales books such as illustrated and described 85 herein.

In making an entry in a book such as shown herein, the operator writes the same upon the original sheet 1, thereby simultaneously making the same record upon the 90 duplicate and triplicate sheets, the record on the duplicate being made upon the under or reverse side thereof and by means of the transfer material on the upper surface of the transfer sheet while the record on the 95 triplicate sheet is made in the ordinary manner, by transfer from the lower of the transfer sheets upon the upper surface of the triplicate sheet. The record which is made upon the under or reverse side of the duplicate sheet will be clearly legible upon the upper or front side because of the striking through of the transfer material from the under or reverse side of such sheet to the upper or front side thereof. The operator, 100 after making his entries, can tear off the original and duplicate sheets from the stub 4. Then, inserting his thumb into the notch 14, he can conveniently grasp the original sheet 1 beneath the carbon sheet and, by pulling downwardly upon the original sheet and moving it upwardly in the manner shown in Figs. 2 and 3, can throw the used triplicate sheet 7 back out of the way in the manner shown in Fig. 3. This enables the carbon 115 sheet to be conveniently inserted above, and in fact to drop upon, the next unused triplicate sheet, and the leaf comprising the unused original and duplicate sheets will automatically drop upon the carbon sheet, ready 120 for the next operation.

While I have illustrated and described one particular use for paper constructed in accordance with my invention, it will be understood that I do not propose thereby to 125 be limited to such use, as it will be evident that other and more important fields of usefulness will be developed therefrom. For instance, the paper is well adapted for use with a typewriter wherein transfer material 130

is carried by the platen as, for instance, in the patent to Farmer, No. 878,717, issued Feb. 11, 1908.

Having thus described my invention, what

5 I claim is:—

1. An integral sheet of paper comprising two sections, one of said sections being impermeable and the other section being permeable to transfer material whereby transfer material taken upon or applied to one side of such section will permeate the latter section and become visible from the other side.
- 10 2. A sheet of paper comprising two sections divided by a severing line, one of said sections being impermeable and the other section being permeable to transfer material whereby transfer material taken upon or applied to one side of the latter section will permeate such section and become visible from the other side.
- 15 3. An integral sheet of paper comprising two sections divided by a severing line, one of said sections being ordinary paper and the other section having incorporated therewith an ingredient which renders it permeable to transfer material applied to either side thereof.
- 20 4. An integral sheet of paper comprising two sections divided by a line of perforations, one of said sections being ordinary paper and the other section having incorporated therewith an ingredient which is substantially solid at ordinary atmospheric
- 25 temperatures but is incorporated into said latter section in a molten condition and

which renders the section permeable to transfer material applied to either side thereof.

5. A manifold tablet comprising a plurality of double sheets, each sheet being divided by a weakened line into upper and under sections, the latter section of each sheet being permeable to transfer material, another sheet beneath the double sheet, and 45 a carbon sheet coated on both sides interposed between the under section of the double sheet and the said additional sheet.

6. A manifold tablet containing a plurality of sets of leaves each set comprising 50 a pair of leaves, one of the sheets of said pair being ordinary paper which is adapted to receive written or printed matter directly thereupon and the other of said leaves having incorporated therewith an ingredient which 55 renders it permeable to transfer material applied to either side thereof.

7. A manifold tablet containing a leaf of ordinary paper adapted to receive written or printed matter directly thereupon, a second leaf beneath said first named leaf having incorporated therewith an ingredient which renders it permeable to transfer material applied to either side thereof, and a carbon sheet coated upon its upper side and 60 positioned directly beneath said second leaf.

In testimony whereof, I hereunto affix my signature in the presence of two witnesses.

CHARLES L. SPENCE.
